(57) **ABSTRACT**

A new and distinct variety of lilac plant having an upright, dense, deciduous shrub which can be trained as a small tree and lilac-colored flowers having a very strong lilac scent, is disclosed.

2 Drawing Sheets

1

Genus and species: *Syringa hybrida*.

Denomination: 'SCHolirofrag'.

BACKGROUND

'SCHolirofrag' is a new and distinct variety of lilac. 'SCHolirofrag' originated from a controlled cross in April 2008 in Somis, Calif. between the female parent, an unnamed and unpatented lilac seedling having lilac-colored flowers, and the commercial male parent, 'Snowy Beach Party' (unpatented).

The resulting seeds from the cross were collected in August 2008 and planted and evaluated in Somis, Calif. 'SCHolirofrag' was selected in April 2012 from the population of seedlings in Somis, Calif. 'SCHolirofrag' was first asexually propagated in April 2014 in Somis, Calif. from two node softwood cuttings rooted under mist at 25 to 27 degrees Celsius. In 2016, 'SCHolirofrag' was subsequently propagated via tissue culture and micro-propagation.

Other subsequent asexual propagations were conducted in controlled environments in Somis, Calif. and Tipp City, Ohio and demonstrate that 'SCHolirofrag' reproduces true to type in successive generations of asexual reproduction via softwood cuttings, tissue culture, and micro-propagation.

SUMMARY

The following are the most outstanding and distinguishing characteristics of this new variety when grown under normal horticultural practices in Somis, Calif. and Tipp City, Ohio.

1. An upright, dense, deciduous shrub which can be trained as a small tree; and
2. Lilac-colored flowers having a very strong lilac scent.

DESCRIPTION OF THE PHOTOGRAPHS

This new lilac plant is illustrated by the accompanying photographs which show the plant's overall plant habit including form, foliage, and flowers. The photographs are of a 3-year old plant grown outdoors in Tipp City, Ohio. The colors shown are as true as can be reasonably obtained by conventional photographic procedures.

5

DETAILED DESCRIPTION

The following detailed descriptions set for the distinctive characteristics of 'SCHolirofrag'. The data which define these characteristics were collected outdoors in Tipp City, Ohio in May 2019 from a 3-year-old plant. The phenotype of this new variety will vary somewhat with variation in environmental, climatic, and cultural conditions as it has not been tested in other environments. Color references are to The R.H.S. Colour Chart of The Royal Horticultural Society of London (R.H.S.) 2001.

15 **Classification:**

Family.—Oleaceae.

Species.—*Syringa hybrida*.

Common name.—Lilac.

Variety.—'SCHolirofrag'.

20 **Parentage:**

Female parent.—An un-named and unpatented lilac seedling.

Male parent.—'Snowy Beach Party' (unpatented).

25 **Propagation:**

Type.—Softwood cuttings.

Time to initiate roots.—In the summer, 18 to 21 days at 25 degrees Celsius.

Time to produce a rooted young plant.—In the summer, 12 to 14 weeks.

Root description.—Fibrous.

Rooting habit.—Well-branched and dense.

30 **Plant description:**

Plant form and growth habit.—Upright, dense deciduous shrub or trained as a small tree.

Branching habit.—Well-branched, dense.

Plant height.—180 cm to 240 cm.

Plant diameter (area of spread).—150 cm to 210 cm.

35 **Lateral branch description:**

Length.—30 cm to 40 cm.

Diameter.—4 mm to 5 mm.

Internode length.—5 cm.

Aspect.—Straight.

Strength.—Strong.

40

Texture, immature.—Finely pubescent.	5	Peduncles:
Texture, mature.—Becomes rough and woody with age.		Length.—6 cm.
Color, immature.—RHS 146B.		Diameter.—25 mm.
Color, mature.—RHS N200B.		Strength.—Strong.
Leaf:		Aspect.—Straight.
Arrangement.—Opposite, simple.	5	Texture.—Smooth, glabrous.
Length.—8 cm to 9 cm.		Color.—RHS 146C.
Width.—6.5 cm to 7.0 cm.		Pedicels:
Shape.—Elliptic-ovate.	10	Length.—3 mm.
Apex.—Acute.		Diameter.—1 mm.
Base.—Cordate.		Strength.—Strong.
Margin.—Entire.		Aspect.—Straight.
Texture.—Upper surface: Smooth. Lower surface: Smooth mid-rib vein prominent.	15	Texture.—Smooth.
Venation pattern.—Pinnate.		Color.—RHS 183A on sun exposed side and RHS 146D on shady side.
Venation color.—Upper surface: RHS 138D. Lower surface: RHS 147C.		Reproductive organs:
Immature leaf color.—Upper surface: RHS 146B. Lower surface: RHS 147C.		Androecium.—Quantity of stamens per flower: 2 to 6. Anther shape: Oblong. Anther length: 7 mm. Anther color: RHS 12C. Amount of pollen: Moderate. Pollen color: RHS 28D.
Mature leaf color.—Upper surface: RHS 137C. Lower surface: RHS 138A.	20	Gynoecium.—Quantity of pistils per flower: 1. Pistil Length: 3 mm. Style length: 1 mm. Style color: RHS N155D. Stigma color: RHS 157A. Stigma shape: Oblong. Ovary color: RHS N155D.
Petioles.—Length: 2.5 cm. Color: RHS 146A. Texture: Smooth.		Fruit and seed set: None observed.
Flower:	25	Disease and insect resistance: Resistant to lilac powdery mildew <i>Erysiphe syringae</i> (formerly <i>Microsphaera syringae</i> and <i>Phyllactinia syringae</i>)
Flower arrangement and flowering habit.—Single, salverform, dense, packed in panicles of up to 150 flowers.		COMPARISON WITH PARENTAL AND COMMERCIAL LINES
Natural flowering season and flower longevity.—Mid-spring, 2 to 3 weeks.	30	Table 1 shows a comparison of differences between 'SCHolirofrag' and both parental lines.
Fragrance.—Very strong lilac scent.		TABLE 1
Inflorescence height.—17 cm to 19 cm.		Comparison with Parental Lines
Inflorescence diameter.—15 cm to 16 cm.		
Inflorescence shape.—Conical.		
Flower diameter.—2 cm.	35	
Flower length.—2 cm.		
Flower buds.—3 mm in diameter, 2 mm long.		
Flower bud color.—N74B.		
Flower bud texture.—Smooth.		
Petals:		
Quantity.—Tubular with 4 petal lobes.		
Lobe length.—10 mm.	40	Characteristic 'SCHolirofrag' Female parent, un-named Lilac seedling Male parent, 'Snowy Beach Party'
Lobe width.—6 mm.		
Lobe shape.—Funneliform.		
Lobe attitude.—Erect to semi-erect.		
Undulation of lobe.—Absent.		
Incurving of margin of lobe.—Medium.	45	
Apex.—Rounded.		
Base.—Fused.		
Margin.—Entire.		
Texture.—Upper surface: Smooth, glabrous. Lower surface: Smooth, glabrous.	50	
Color.—Upper surface: RHS N74C. Lower surface: RHS 72D.		
Sepals:		
Quantity & arrangement.—Very small and inconspicuous.	55	
Length.—1 mm.		
Width.—1 mm.		
Shape.—Lanceolate.		
Apex.—Acute.		
Base.—Fused.		
Margin.—Entire.		
Color.—Upper surface: RHS N77A on side facing sun, shaded side is RHS 146D. Lower surface: RHS 146D.	60	

Table 2 shows a comparison of the differences between 'SCHolirofrag' and the commercial Lilac variety 'Yankee Doodle' (unpatented).

TABLE 2

Comparison with Commercial Line		
Characteristic	'SCHolirofrag'	'Yankee Doodle'
Flower color, upper surface	RHS N74C	RHS 77A
Flower color, lower surface	RHS 72D	RHS 77B
Plant height	180 cm to 240 cm	240 cm
Plant diameter	150 cm to 210 cm	210 cm
Flower color, upper surface	RHS N74C	RHS 155C
Flower color, lower surface	RHS 72D	RHS 76B

I claim:

1. A new and distinct variety of lilac plant designated 'SCHolirofrag' as illustrated and described herein.

FIG. 1

FIG. 2
